UNITED STATES PATENT OFFICE.

RAMON BOVÉ, OF NEW YORK, N. Y.

HAIR-WAVING MACHINE.

979,058

Specification of Letters Patent. Patented Dec. 20, 1910.

Application filed December 8, 1909. Serial No. 532,098.

To all whom it may concern:

Be it known that I, RAMON BOVÉ, citizen of Spain, residing at New York, in the county of New York and State of New York, have invented certain new and useful Improvements in Hair-Waving Machines, of which the following is a specification.

The primary object of this invention is an improved hair waving apparatus which will 10 be simple and durable in construction and efficient in operation to wave a person's hair without injuring the same.

The invention consists essentially in a hair waving apparatus embodying two sets 15 of bars that are arranged to fold one set upon the other with the hair between them, mild heat being applied to the device as through the instrumentality of an electrically heated plate so as to maintain the wavy 20 condition in which the hair is retained as it lies in between the folded bars.

The invention also consists in a device of this character in which the bars are extensibly arranged relative to each other so that 25 after one set has been folded over upon the other set, the folded sets may be moved or crowded toward one end of the device so as to wave the hair not only by the hair being caught in between the folded bars but be- 30 tween one pair of folded bars and the next pair.

The invention further consists in a hair waving apparatus embodying improved means whereby covers between which the 35 two sets of bars are placed may be easily held in a spread out condition so as to provide for the ready placing of the hair in the apparatus, means being also provided whereby upon the releasing of such cover holding 40 means, the two sections or plates of the cover with the bars between them may be easily folded one upon the other, the apparatus thus automatically acting to move the 45 folded bars toward each other in a longitudinal direction.

Conversely, the invention consists in a device whereby the movement of one cover plate away from the other to open the apparatus will automatically spread the bars 50 apart in a longitudinal direction while the sets of bars are opened out or unfolded so as to permit the waved hair to be removed. And the invention also consists in certain 55 constructions, arrangements and combinations of the parts that I shall hereinafter fully describe and claim.

Figure 1 is an inner face view of a hair waving machine constructed in accordance with my invention; Fig. 2 is an outer face view thereof, parts being broken away, and other parts being shown in section; Fig. 3 is a longitudinal sectional view of the device with the parts closed; Fig. 4 is a transverse sectional view thereof; and, Fig. 5 is a fragmentary longitudinal sectional view on an 65 enlarged scale.

Corresponding and like parts are referred to in the following description and indicated in all the views of the accompanying drawings by the same reference characters.

My improved hair waving apparatus embodies any desired number of bars arranged in pairs hingedly connected together at one end and designed to be folded one upon the other. The bars of the set which in the operation of the device are lowermost are 75 designated 1 and their corresponding bars 2.

Each bar is preferably formed with perforations 3, and each lowermost bar 1 is also formed with side flanges formed with 80 relatively short teeth 4, the teeth being of any desired number and at any desired intervals apart. The bars 1 are connected together for a lateral and extensible movement by means of links 5 secured thereto at or 85 near the ends of the bars, said links being joined together by a pin and slot connection as indicated at 6. The bars 2 are similarly connected near their relatively free ends by corresponding bars 5 having pin 90 and slot connections with each other to effect the movement of the bars 1 toward each other, it being of course understood that this movement is not performed in the actual operation of the device until the bars 95 2 have been folded upon the bars 1; toggle bars 7 are connected to the bars 1 and have suitable slot and pin connections with alternating bars whereby when one end of the bar 1 is pressed open by coil springs 8 as 100 indicated in Fig. 2, the entire set of bars will be pushed toward the opposite end bar 1. Preferably the springs 8 work in tube

covered slots 9 formed in a cover plate 10 and one end bar 1 is rigidly connected to the cover plate 10 as by rivets 1^a or similar fastening devices. The cover plate 10 is connected by hinges 11 to a corresponding cover plate 12 the said cover plate being of any desired design and of a size to conveniently hold the two sets of bars 1 and 2 in the spread out condition thereof as indicated in 110

Fig. 1. Preferably the end bar 1 which is pressed upon by the expansion springs 8 has an end rivet 13 movable in a slot 14 formed in the cover plate 12.

5 In order to swing one cover plate over upon the other and fold one set of bars against the corresponding bars of the other set, I have provided a chain or cord 15 which is secured at one end to the cover plate 12 10 and which extends transversely over upon the cover plate 10 where it is connected to the adjacent end bar 1. Also connected to this end bar 1 is a compression or contractile spring 16, said spring being also connected 15 to the cover plate 10. The cord 15 it will be understood has such a running connection with the cover plate 10 that the contraction of the spring 16 will tend to draw the cover plate 12 over upon the cover plate 10 and 20 also draw the end bar 1 just mentioned inwardly toward the rigidly connected end bar 1. Conversely, it will be understood that the opening of the cover plates will place the spring 16 under tension and at the same 25 time tend to draw the loose end bar 1 away from the rigidly connected end bar so as to spread all of the bars out to the position illustrated in Fig. 1, the intermediate bars being moved by the toggle link connections 30 7 before described. Of course the springs 8 are the main elements for crowding the bars together in a longitudinal direction after the device has been closed.

In order to hold the device open the cover 35 plate 12 is provided with a transversely extending finger 17 secured in any desired way thereto and extending across the hinge 11 to the other cover plate, a longitudinally movable latch 18 being mounted on said last 40 named cover plate and being firmly pressed into engagement with said finger by means of an expansion spring 19. In order to retract the latch from the finger or keeper 17 and permit the device to close, I have provided 45 a chain or cord 20 which extends through the spring and is connected to the latch at one end, the other end of the cord being connected to a releasing arm or bell crank 21 mounted in a handle 22 which extends perpendicularly from the outer face of 50 the cover plate 10.

The entire device is carried by the handle 22 as it is placed in position next to the scalp and the incorporation of the releasing arm 55 21 in said handle renders it possible to release the latch 18 from the keeper 17 by a finger of the same hand which grasps the handle, the other hand of the operator being left free to lay the hair out along the lower 60 side of the bars 1 and to see that the device is properly closed upon the hair.

To open the device pull handles 23 are provided, the same being secured to the outer face of the cover plates 10 and 12.

65 24 designates a heating plate, which is con-

nected in any desired way to the cover plate 10, feed wires 25 leading into and out of said plate so that when said wires are connected to an incandescent electric light socket a mild heat will be produced so as to effectually wave the hair without injuriously affecting the same. This electrical heating plate may be of any desired construction. The cover plate 10 is formed with a concave end from which comb teeth 26 project. 75

From the foregoing description in connection with the accompanying drawings, the operation of my improved hair waving apparatus will be apparent. In the practical use of the device, the operator grasps the handle 22 with the apparatus open and inserts the comb 26 up underneath the hair next to the scalp, the hair being then laid over upon the lower set of bars 1. The latch 18 is then released and the cover plate 12 80 moved over upon the cover plate 10, the spring 16 and cord 15 assisting in this movement, the bars 2 being then folded upon the bars 1 by this action and the folded bars being then moved toward each other in a 85 longitudinal direction by means of the expansion springs 8. It will then be seen that the hair will be effectually waved, as the electricity is then turned on to heat the device and that the hair will be very quickly 90 waved and without injuring the hair or without any inconvenience or discomfort to the person being treated.

By providing the bars 1 with side flanges between which the bars 2 lie in the folded 100 position of the two sets of bars, the hair is held in a wavy condition within the bars as well as between every two pairs of bars, and by providing the bars 1 with teeth 4, it is obvious that the hair will be better held than 105 would be the case if the flanges of the bars were smooth.

Having thus described the invention, what is claimed as new is:

1. A hair waving apparatus, comprising 110 two sets of bars containing a plurality of bars in each set, the bars of one set being hingedly connected to the bars of the other set and arranged to be folded one upon the other, and means for automatically moving 115 the bars toward each other in a direction lengthwise of the set upon the folding movement of the bars.

2. A hair waving apparatus, comprising 120 two sets of bars containing a plurality of bars in each set, the bars of one set being hingedly connected to the bars of the other set and arranged to be folded one upon the other, means for automatically moving the bars toward each other in the direction 125 length-wise of the set upon the folding movement of the bars, and means for automatically spreading the bars apart in a direction lengthwise of the set upon the unfolding movement of the bars. 130

3. A hair waving apparatus, comprising two sets of bars, one set being arranged to fold upon the other set, the bars being formed with perforations, and the bars of the set being provided with flanges between which the other bars are adapted to lie, said flanges being formed with teeth.
4. A hair waving apparatus comprising two sets of bars, the bars of one set being arranged to fold over upon the bars of the other set, cover plates carrying said bars, and springs carried by one of said cover plates and connected to the end bars of one set and arranged to move the folded bars to ward each other in a direction lengthwise of the sets.
5. A hair waving apparatus comprising two sets of bars the bars of one set being arranged to fold over upon the bars of the other set, cover plates arranged to support the bars, a toggle link connection between the bars of one set, one end bar of one set being rigidly connected to one cover plate, and expansion springs pressing upon the opposite end bars of the same set, for the purpose specified.
6. In a hair waving machine, the combination of two sets of bars, the bars of one set being arranged to fold over upon the bars of the other set, cover plates arranged to support said bars, means carried by one of said cover plates for crowding the bars to one end of said cover plate, and means tending to fold one cover plate upon the other and arranged to extend the bars upon the opening movement of the cover plates.
7. In a device of the character described, the combination of two sets of bars, the bars of one set being arranged to fold over upon the bars of the other set, cover plates arranged to support the bars, the cover plates being hingedly connected together, a finger secured to one cover plate, a handle connected to the other cover plate, a releasing arm carried by the handle, a spring pressed latch carried by said last named cover plate and adapted to engage the finger and hold the plates in extended or open position, and a releasing cord connected to said latch and to the releasing arm.
8. A hair waving apparatus comprising two sets of bars, the bars of one set being arranged to fold over upon the bars of the other set, and cover plates supporting said bars, one of the cover plates being formed at one end with comb teeth.

In testimony whereof I affix my signature in presence of two witnesses.
